MACHINE FOR TREATING WOOD PULP

James T. Coghill, Fairport, N. Y., assignor, by
mesne assignments, to Cirlater Corporation,
Rochester, N. Y., a corporation of New York

Application December 30, 1948, Serial No. 68,207

9 Claims. (Cl. 92—26)

1

The present invention relates to machines for processing fibrous material and particularly to machines for processing wood pulp for making paper. More particularly, the present invention relates to machines for mechanically processing wood pulp according to the method disclosed in the Hill and Edwards U. S. patent application Serial No. 565,128, filed November 25, 1944, now Patent No. 2,516,384, granted July 25, 1950. In a still more specific aspect it is the purpose of the present invention to provide an improvement upon the machine of my pending U. S. patent application Serial No. 773,012, filed September 9, 1947, now Patent No. 2,622,490, granted December 23, 1952.

In the machine of my prior application mentioned, the pulp, which is to be treated, is fed through a central inlet onto a drainage plate where it is thickened and is picked up by sweep arms and moved onto a stationary lower working surface which surrounds the drainage plate. The thickened pulp is rolled between a gyrating upper working surface and the lower working surface under pressure. Periodically, the upper working surface may be moved toward and from the lower working surface to control the traverse of the material, which is being treated, between and over the working surfaces from the entry zone to a discharge zone around the periphery of the lower working surface. The movement of the upper working surface toward and from the lower working surface is effected hydraulically under control of cams. At the discharge zone the pulp falls into a trough which has a helical bottom, and it may be sluiced down this trough to a discharge outlet.

A principal object of the present invention is to provide a machine which will be more efficient in operation and of simpler construction than the machine of my prior application above mentioned.

Another object of the invention is to provide a machine in which separate means for moving the upper working surface toward and from the lower working surface is eliminated, and in which the gyratory motion of the upper working surface in itself causes variation in the distance between the upper and lower working surfaces, thereby alternately increasing and decreasing pressure on the pulp being treated and controlling the traverse of the material over and between the working surfaces.

Another object of the invention is to provide in a machine of the character described improved means for carrying off the treated pulp from the discharge zone of the machine.

2

Still another object of the invention is to provide a machine of the character described which is equipped with means for heating the pulp or other material being treated so as to improve its workability.

Other objects of the invention will be apparent hereinafter from the specification and from the recital of the appended claims.

In the drawings:

Fig. 1 is a fragmentary view, partly in side elevation and partly in vertical section, of a machine built according to a preferred embodiment of this invention;

Fig. 2 is a fragmentary vertical sectional view on an enlarged scale showing in greater detail the sweep mechanism, the upper and lower working surfaces, the turn table for carrying off the treated pulp, etc;

Fig. 3 is a fragmentary sectional view on a still further enlarged scale showing in detail one of the steam jets for heating the pulp, and its mounting;

Fig. 4 is a fragmentary plan view, with parts broken away, showing further details of the de-watering area, sweep arms, lower working surface, turn table, and stock outlet;

Fig. 5 is a fragmentary plan view, with parts broken away and on a reduced scale, showing details of the mechanism for insuring parallel bodily movement of the upper working surface;

Figs. 6 and 7 are diagrammatic views illustrating the motion and action of the working surface of the machine;

Fig. 8 is a fragmentary sectional view on a greatly enlarged scale of portions of the working surfaces of the machine; and

Fig. 9 is a fragmentary plan view of one of these working surfaces.

The machine illustrated in the drawings, like the machine of my prior application, has a centrally disposed de-watering area in which the consistency of the stock is raised and in which the stock is nodulated, a lower working surface, which is stationary and which surrounds the de-watering area, and an upper working surface which is given a continuous gyratory or orbital motion during operation of the machine and which extends over both the de-watering area and the lower working surface.

The pulp, which is to be treated, as in the machine of my prior application mentioned, enters the de-watering area of the machine from below through a continuously rotating hollow shaft and fans out over an internal conical perforated de-watering plate which surrounds this shaft. A sweep head having a plurality of lateral-

ly extending arms which extend over the de-watering surface, is secured to this shaft; and as the shaft rotates, the sweep arms gather the stock from the surface of the de-watering plate and press it up against the gyrating upper plate while at the same time urging it radially outward.

In the machine of the present invention, the upper working surface is dished upwardly, that is, it is an internal conical surface above the sweep arms and above the portion of the lower working surface which surrounds the drainage area. As the upper working surface gyrates, then, the nodules of stock are rolled between the concave portion of the upper working surface and the opposed surfaces of the sweep arms and of the lowering working surface. During half of a revolution of the upper working surface, then, there is a reduction in clearance between the upper working surface and the sweep arms and the lower working surface, which increases the compression of the pulp and tends to cause slippage of the nodules on the upper plate. This causes the nodules to traverse the upper plate and leaves them a little farther out than they would be if this slippage did not occur. On the other half of the revolution of the upper plate the clearance increases and the nodules roll without slippage. The net result is an outward traverse of the nodules and a periodic variation in the clearance between the working surfaces.

Both upper and lower working surfaces are knurled, and in the inner portions of these surfaces, at least, the knurls or protuberances are inclined and directed outwardly so as to help the traverse of the material over the surfaces toward the discharge zone. When the pulp reaches the edge of the lower working surface, it drops onto a turntable which extends around the lower working surface and which rotates continuously. It is carried around by this turntable to a doctor or arm which overlies the turntable and which directs it into a discharge outlet. The white water, which has been extracted from the stock in the de-watering zone, may be carried to this outlet to sluice the stock away. If desired, this white water may restore the stock to approximately the same fluid state in which it entered the machine so that it can be carried easily for further treatment. A simple flap valve, governed by a weight, is provided to control the flow of white water into the discharge outlet. By adjustment of this valve a back-pressure can be applied to regulate the rate of feed of the stock through the machine.

As the thickened stock moves onto the lower working surface it may be heated by steam jets located in the lower working surface around the de-watering area. It has been found that stock will roll and traverse more readily when heated and that greater pressure can be applied thereto without danger of setting up shear planes in the stock. In some cases this heating is necessary in order to obtain curling of the stock and prevent smearing of the stock on and between the working surfaces. The stock is heated after it is de-watered because this reduces the amount of heat (steam) required and enables the heat (steam) to be employed most effectively.

Referring now to the drawings by numerals of reference, 28 denotes the base or bed of the machine. Journaled in this base or bed in any suitable manner is a hollow shaft 24 (Figs. 1 and 2) which is internally threaded at its upper end to receive and engage the externally threaded portion of a rotary sweep head 25. The sweep head is provided with a plurality of radially extending

sweep arms 28 that extend outwardly from the head and are of longitudinally spiral shape (Fig. 4). These arms are generally similar to the sweep arms 28 of the machine of my prior application above mentioned. The front faces of these arms may be convex but they differ from the sweep arms of my prior application in that they have upper surfaces 30 which lie in an external conical surface coaxial with the axis 32 of the shaft 24 and sweep head 25. The front and upper surfaces of the sweep arms may be smooth, although they can also be roughened or knurled if desired.

The shaft 24 may be driven from a motor (not shown) through the bevel gears 33 and 34 (Fig. 1), the shaft 37, the spur pinion 38 and spur gear 39. Gear 34 is keyed or otherwise secured to shaft 37 and pinion 38 is integral with that shaft. Gear 39 is fastened in any suitable manner to shaft 24.

As the sweep head rotates, its arms 28 travel over a perforated internal conical drainage or de-watering plate 31 (Figs. 2 and 4) which is concentric with sweep head 25. This plate has a plurality of spaced, flat straps 21 secured to its upper surface. These straps are fastened so that they extend obliquely across the drainage surface, being tangent to a circle concentric with the drainage surface; and they are arranged preferably as shown, so that they are disposed about the axis of the drainage surface to have the opposite hand of inclination from the hand of spiral of the sweep arms 28. The straps 21 are narrow and relatively thin.

The under surfaces 29 of the sweep arms have the same general cone angle as the conical upper surface of the drainage plate. The clearance between the bottom surfaces 29 of the sweep arms and the upper surface of the drainage plate may be determined by axial adjustment of the sweep head 25 in the shaft 24; and is so adjusted that the sweep arms readily clear the straps 21. As the sweep head rotates, then, the sweep arms sweep pulp up off the drainage plate. The skew straps 21 prevent the stock from sliding around on the drainage surface, if the stock is slippery; and they help cause the stock to progress outwardly as the sweep arms pass over them.

The de-watering plate is secured by riveting or in any other suitable manner to a casting 35 that has a conical upper surface and that is fastened by screws 36 to the base 20 of the machine. The casting 35 has holes 35' in it beneath drainage plate 31 so that the white water expressed from the pulp may flow from the drainage plate into a conduit as will be described further hereinafter.

The aqueous slurry of pulp, which is to be treated, is supplied to the machine through a pipe 55 (Fig. 1) which communicates and registers with the bore of the shaft 24.

Surrounding the de-watering area and coaxial therewith is the lower working surface of the machine which is designated as a whole at L. This is circular and comprises a plurality of sectoral knurled plates 40, which are riveted to a supporting shoe 41 that in turn is secured by screws 42 to the base 20, and a plurality of sectoral knurled plates 44, that are riveted to a plate 45 which in turn is riveted to a plurality of sectors forming a ring 46. The sectors of ring 46 are clamped against one wall of an outer shoe 48 by clamping screws 47 that adjustably thread into the outer shoe 48 and that are adapted to abut against the sectors. The shoe 48 is secured by screws 49 to the base 20. The

plate 45, which supports the plates 44, is adapted to engage under the plates 40 and is held in that position by the clamping screw 47.

The plates 40 and 44 are shown, like drainage surface 31, only fragmentarily in Fig. 4. It is to be understood, however, that drainage surface 31 fully overlies casting 35, and that plates 40 and 44 together constitute a full circular working surface coaxial with the sweep head and drainage surface.

Mounted above the sweep arms 28 and the lower working plates 40 and 44 and in opposed relation thereto is the circular upper working surface of the machine which is denoted as a whole at U. This comprises a plurality of sectoral knurled plates 50 and 54 (Fig. 2) which are riveted to plates 51 and 52, respectively. The plates 51 are riveted at their outer ends to a plurality of sectors constituting a ring 53, which are clamped against a rib 55 of the driving plate 56 by clamping screws 57. At their inner ends, the plates 51 are held to the driving plate 56 by a gib plate 58 which is riveted to a plate 59 that in turn is riveted to a plurality of sectors forming a ring 60. These are secured by screws 61 to the driving plate 56.

The plate 52 is held against the driving plate by the overlapping working surfaces 50 at one end. The plate 52 is also riveted to a plurality of sectors constituting a ring 63 which are held against a rib 64 of the driving plate 56 by clamping screws 65. The under surface of the portion of the driving plate 56, which lies above the lower working plates 44, is in a plane parallel to the plane of the lower working plates and as a result, the working surfaces of the upper plates 54 are parallel to the working surfaces of the lower working plates 44. The portion of the under surface of the driving plate 56 around the hub of that plate is, however, upwardly dished and the working plates 50 are secured to this portion of the driving plate so as to follow this upward or inward dish. Thus the working plates 50 form a concave conical working surface. The cone angle of this surface is preferably made to be within four or five degrees of the cone angle of the upper surfaces 38 of the sweep arms 28.

The hub of the driving plate 56 is secured by screws 70 to the journal or sleeve 71 which is mounted within a bearing 72. This bearing 72 has convex spherical surfaces which seat within concave spherical surfaces formed in blocks 74 and 75, respectively. Block 75 has a counterweight 76 secured to it. Block 74 is fastened by bolts 78 and nuts 79 to the head or flange 80 of a crank shaft 81. The axis 84 of the driving plate 56 is, therefore, offset from the axis 82 of shaft 81; and the shaft imparts to the driving plate an eccentric motion. The shaft 81 is adapted to be driven from a motor (not shown) through the shaft 35 (Fig. 1) and the spiral bevel gears 86 and 87, the hub of the latter gear being keyed or otherwise secured to the shaft 81.

During operation of the machine, a predetermined pressure is applied to the upper working surface to apply a predetermined load to the pulp being treated. The load is applied by hydraulic pressure so that the upper working surface is free to float toward and from the lower working surface. The hydraulic pressure is applied to the upper ends of a pair of pistons 90 (Figs. 1 and 5) which are housed in cylinders 91 that lie at diametrically opposite sides of crank shaft 81. The cylinders 91 are secured

by bolts 92 to blocks 93 which are in turn secured by bolts 94 to the upper framework 95 of the machine. Each piston 90 has a hole extending diametrically through it which is adapted to receive the rounded inner ends of two aligned arms 96 that are secured by bolts 97 to rocker members 100. The rocker members 100 are mounted at opposite sides of crank shaft 81 to rock on trunnions 101 that are secured by screws 102 to the framework 95. Mounted in each of the rocker members 100 are two heads 105 that are secured to the rocker members by bolts 106. These four heads 105 are connected by Cardan joints or gimbals 107 with four rods 108, each of which extends through aligned openings 109 and 110 in a rocker member 100 and the framework 95. At their lower end, the four rods 108 are connected by other Cardan joints or gimbals 112 with four plates 113 (Figs. 1 and 2) that are bolted at equi-spaced points to the drive plate 56.

The rods 108 constrain the upper working surface so that as crank shaft 81 rotates all points in the upper working surface will travel in circles of equal radius. The hydraulic pressure on the upper surfaces of the pistons 90 applies a load to the pulp being rolled between the upper and lower working surfaces of the machine. Through use of a fluid medium for application of pressure, the upper working surface may float under predetermined load within the permissible limits of movement of pistons 90. The rocker members 100 and arms 96 insure uniform application of this load all over the upper working surface. They also insure that the upper working surface U moves parallel to itself as it moves up or down, and cannot tilt.

In the machine of my prior U. S. patent application Serial No. 773,012, means is provided for moving the upper surface cyclically toward and from the lower working surface. In the machine of the present invention this cyclical movement is accomplished without any separate mechanism but simply by the gyroscopic motion of the upper surface itself because of the internal conical construction of that surface. This is illustrated diagrammatically in Figs. 6 and 7.

As the axis 84 of the upper working surface U rotates about the axis 82 of crank shaft 81, axis 84 will travel in a circle 115 (Fig. 6) concentric to axis 82 (Fig. 6). The position of the upper working surface is indicated diagrammatically in full lines at A in Fig. 7 when the axis 84 of the gyroscopic plate 56 is at 84' (Fig. 6). B denotes diagrammatically the position of the upper working surface when the axis 84 of the upper working surface has rotated through an angle of 180° about the axis 82 of the crank shaft to the position 84'' (Fig. 6).

The effect of the gyroscopic motion of the upper working surface and of its concave conical shape is alternately to squeeze and release the nodules N of pulp between the upper and lower working surfaces and between the upper working surface and the sweep arms 28. When the motion of the upper working surface is from A to B, a nodule N is squeezed down and rolled to the position N'. The reduction in clearance between the upper and lower working surfaces on the inward stroke increases the compression and tends to cause slippage of the nodule on the upper working surface U, thus leaving the nodule a little farther out than it would be without slippage. The nodule rolls during this motion a distance D equal approximately to one-half the total motion 75 G of the eccentric movement of the upper work-

ing plate. On the outward stroke of the upper plate from B to A the clearance increases and the nodule rolls without slippage on the lower working surface L. The net result of the gyroscopic motion is an alternate increase and decrease in pressure and a traverse outward of the nodule.

To increase the outward travel, the knurls or protuberances of the upper and lower working surfaces are preferably made directional at least in the cupped zone of the upper working surface. In other words, the plate 50 and the plates 40 are provided with inclined projections or protuberances 120 and 121, respectively, that lean outwardly toward the discharge zone of the machine. Such knurls or protuberances are less resistant to slippage of the rotatable pulp units in the direction in which they lean.

In order to permit rollwise traverse of the pulp nodules or of rotatable units thereof over and between the working surfaces, the pointed protrusions should be spaced adjacent to one another a distance of from two to three times their height. If the spacing is too close, the cavities between the points may fill up with stagnant pulp and the surfaces will not be self-cleaning which is a necessary condition in obtaining the required rollwise traverse. If the pointed protrusions are spaced too far apart, the gripping action on the nodules or on rotatable units thereof is diminished and the required rollwise traverse can not be achieved at as high a speed or under as high compression. The directional working surfaces may be made as described in my earlier application Serial No. 773,012 above mentioned.

Through traverse of the pulp over the lower working surface, the nodules are carried on to the discharge zone at the periphery of the lower working surface. The treated stock drops off of the lower working surface at this point onto a rotary turntable 125 which is mounted on the machine to be below the lower working surface, but to surround the lower working surface, as shown in Fig. 2. The turntable 125 is adapted to be driven from a motor (not shown) through the shaft 26, bevel gears 127 and 128, shaft 129, spur pinion 130 and spur gear 131. The pinion 130 and bevel gear 128 are secured to shaft 129 adjacent opposite ends thereof. The spur gear 131 is secured to or integral with the turntable.

Mounted at one side of the machine is a hopper 135 (Figs. 2 and 4). Secured to this hopper by a bolt 137 is a bracket 138 and mounted upon this bracket is a doctor or arm 139 which extends over the turntable. This doctor is adapted to deflect stock carried around by the turntable into the hopper 135. This hopper has a discharge opening 140 at its bottom through which the pulp may drop into a container or onto a conveyer.

The white water expressed from the pulp in the de-watering area of the machine may be used to slush the treated pulp out of the hopper 135. For this purpose an annular chamber 145 (Fig. 2) may be secured beneath the de-watering area of the machine, and a conduit 147 may be provided to connect this chamber 145 with the hopper 135. A damper 150 may be provided at the mouth of the conduit 147 to control flow of the white water out of the conduit and thereby exert a back-pressure on the white water to control to a degree the traverse of the pulp through the machine. The damper restricts the flow of white water from the pulp and thereby aids in regulating the through-put of the machine.

The damper 150 is integral with an arm 152 that is fastened to a shaft 152. This shaft is

75 journaled in bearings formed at opposite sides of the hopper 135. It has secured to it at one end an arm 154 on which is adjustably mounted a weight 155. By adjusting this weight along the arm 154, the back-pressure exerted by the damper can be controlled.

An apron 156 is secured by screws 157 to one side of the turntable, and an apron 158 is secured by screws 159 to a bracket or ring member 160 which surrounds the turntable and which is suitably mounted on the base of the machine. These aprons serve to prevent the stock from falling off of the turntable until it reaches the doctor 138. The apron 158 has an opening in it, of course, opposite the hopper 135, as shown in Fig. 3 through which the pulp may flow into the hopper. There is a plate 161 secured to the hopper 135 parallel to the doctor 138 so that the stock is guided into the hopper.

It has been found in the cases of some stocks that if the stock is too cold, it will not form into nodules and it will tend to shear, instead of to roll, under normal pressure. Means has been provided in the present machine, for heating the stock to raise its temperature sufficiently for it to curl. This means comprises a steam manifold 165 (Fig. 2) which is mounted beneath the lower working plates 40. Nozzles 167 are threaded into this manifold at angularly spaced points. These nozzles register with openings 168 in the working plates 40. Steam is supplied to the manifold 165 from a pipe 169, and is directed by the nozzles 167 at the de-watered pulp swept onto the plates 40. This steam heats up the de-watered pulp and permits it to be worked by the machine.

In the operation of the machine, it will be seen that the stock, which is of low density, enters the working area of the machine through the pipe 55, the bore 27 of the shaft 24, the bore 26 of the sweep head 25 and the spaces between the sweep arms 28. It fans out over the de-watering plate 31 and up against the gyrating upper working plates 50. As it spreads out over the de-watering plate 31, the white water drains from the pulp through holes in the drainage plate and through the holes 35' in the casting 35 into the chamber 145 whence it flows through the conductor 147 to the hopper 135. As the sweep head rotates, the sweep arms clear the thickening stock from the surface of the de-watering plate 31 while at the same time squeezing portions of the stock between the upper surfaces 30 of the sweep arms and the opposed upper working plates 50. The rotating sweep arms, aided by the straps 21, also urge the thickening stock radially outwardly over the de-watering surface onto the lower working plates 40. There it may be heated by steam from the nozzles 167.

The upper working surface U is, of course, moving in an orbital path under the actuation of the crank shaft 31. Hence, as the stock is carried between the sweep arms and the upper working surface and between the lower working surface and the upper working surface, it is alternately squeezed and released and it is rolled traversingly in different tangential directions in tractive contact with these surfaces. Thus, it is formed into small, discrete nodules of pulp in which the fibres are curled and twisted upon one another. By the time the stock has reached the limit of the de-watering zone, it has been thickened to a consistency of 10 to 20% or more and is substantially completely nodulated. From 75 this point, the nodules are gripped and vigor-

ously rolled between the upper and lower working surfaces while they are caused to progress outwardly toward the periphery of the lower working surface. In their outward travel, the nodules are grouped and re-grouped into units which are rolled traversingly tangentially in different directions in tractive contact with and between the working surfaces and are continuously reoriented with reference to the direction of applied pressure.

When the pulp reaches the edge of the lower working surface it falls onto the turntable 125 which is continuously rotating. It is moist and may be sticky but when it is carried around by the turntable to the doctor 138, the doctor forces it off mechanically into the hopper 135. It drops through the opening in the bottom of the hopper into containers or onto a conveyor by means of which it may be carried on for further treatment. The white water flowing through the conductor 147 will sluice the pulp down to the discharge outlet 140. This water may at the same time help convert the nodulated pulp to a dispersed fibre suspension state in which it can readily be handled for further processing if desired. The damper 150 serves to control the back pressure, and is one of the controls on the rate of feed of the pulp through the working surfaces.

While the invention has been described in connection with a machine for treating raw wood pulp, it will be understood that it may be used as is or with modifications known to the art for treating fibrous material in other forms. Thus it may be used in de-inking and reclaiming waste printed stock according to the process of the joint application of Harold S. Hill and myself, Serial No. 681,918, filed July 8, 1946, now Patent No. 2,641,164, granted June 9, 1953. In such case, both upper and lower working surfaces will preferably be perforated for flow of water or other liquid into and out of the stock being treated as described in application, Serial No. 681,918.

In general, it may be said that while the invention has been described in connection with a particular embodiment thereof, it is capable of further modification, and this application is intended to cover any variations, uses, or adaptations of the invention following, in general, the principles of the invention and including such departures from the present disclosure as come within known or customary practice in the art to which the invention pertains and as may be applied to the essential features hereinbefore set forth and as fall within the scope of the invention or the limits of the appended claims.

Having thus described my invention, what I claim is:

1. In a machine for processing papermaking pulp, a pair of working plates having opposed working surfaces disposed to form between them a thin working space and which are roughened to provide traction for nodules of pulp without obstructing rolling traverse of the nodules on the working surfaces, means for pressing one plate toward the other to compress the pulp between the opposed working surfaces, and means for imparting a translatory gyratory motion to one of said plates about an axis extending in the direction of compression, the working surface of the gyratory plate having a central portion which is internally dished away from the opposed working surface of the other plate, and the area of the working surface of said other plate which is opposed to said internally dished portion of the gyratory plate being inclined to said inter-

nally dished portion at an angle no greater than the angle between said internally dished portion and a plane perpendicular to said axis, whereby the clearance between opposed portions of the working surfaces is periodically varied as the gyrating plate gyrates about its axis so that the nodules of pulp between said internally dished portion and said opposed area are alternately compressed and released and are traversed outwardly toward the peripheries of said working surfaces as said gyratory plate gyrates about its axis.

2. In a machine for processing papermaking pulp, a pair of working plates having opposed working surfaces disposed to form between them a thin working space, both said working surfaces having tiny, spaced protuberances formed thereon projecting into the working space to provide traction for nodules of pulp without obstructing rolling traverse of the nodules on the working surfaces, fluid-pressure operated means for pressing one plate toward the other to compress the pulp between the working surfaces, means for imparting a translatory, gyratory movement to one of said plates about an axis extending in the direction of compression, the working surface of the gyratory plate having an internally dished conical portion and the other working surface having a plane area opposed to said dished portion which is perpendicular to the axis of gyration, whereby the clearance between the working surfaces is periodically varied as the gyratory plate gyrates about its axis and the nodules of pulp are traversed outwardly toward the peripheries of the working surfaces as said gyratory plate gyrates about its axis.

3. In a machine for processing papermaking pulp, a perforated drainage plate, an inlet disposed centrally of said drainage plate through which an aqueous slurry of pulp may be delivered to said drainage plate, a sweep arm rotatable about an axis coaxial with said inlet for sweeping the thickening stock up off said drainage plate, a lower working member having a working surface surrounding said drainage plate, an upper working member overlying both said sweep arm and said lower working member and cooperating with both, said upper working member having a working surface opposed to the working surface of the lower working member which has an internally dished central portion overlying both said sweep arm and the adjacent surrounding part of the working surface of said lower working member, the area of the working surface of said lower member which is opposed to said internally dished portion being inclined to said internally dished portion at an angle no greater than the angle between said internally dished portion and a plane perpendicular to said axis, both said working surfaces being formed with tiny, spaced protuberances thereon to provide traction for nodules of pulp without obstructing rolling traverse of the nodules on the working surfaces, means for pressing one of said working members toward the other to compress pulp between them, and means for imparting a translatory gyratory motion to said upper working member about an axis extending in the direction of compression and perpendicular to said plane.

4. In a machine for processing papermaking pulp, a perforated drainage plate, an inlet disposed centrally of said drainage plate through which an aqueous slurry of pulp may be delivered to said drainage plate, a sweep arm rotatable about an axis coaxial with said inlet for sweep-

ing the thickening stock up off said drainage plate, a lower working member having a working surface surrounding said drainage plate, an upper working member having a working surface overlying both said sweep arm and the working surface of said lower working member and cooperating with both, the upper surface of said sweep arm being an external conical surface coaxial with said sweep arm and the portion of the working surface of the upper working member, which overlies the sweep arm and the part of the lower working member that is adjacent the drainage plate, being an internal conical surface whose axis is parallel to the axis of said sweep arm, said part of the working surface of the lower working member that is adjacent the drainage plate being a plane surface perpendicular to the axis of the sweep arm, both of said working surfaces having tiny, spaced protuberances formed thereon to provide traction for nodules of pulp without obstructing rolling traverse of the nodules on the working surfaces, means for pressing one of said working members toward the other to compress the pulp between them, means for rotating the sweep arm, and means for imparting a gyratory movement to the upper working member about an axis extending in the direction of the axis of the sweep arm.

5. In a machine for processing papermaking pulp, a perforated drainage plate, an inlet disposed centrally of said drainage plate through which an aqueous slurry of pulp may be delivered to said drainage plate, a lower working member having a working surface surrounding said drainage plate, an upper working member having a working surface overlying the working surface of the lower working member and having opposed relation thereto, both said working members having their opposed working surfaces roughened to provide traction for nodules of pulp without obstructing rolling traverse of the nodules on said opposed faces, sweep means for moving thickened pulp from said drainage plate onto the working surface of the lower working member, means for pressing one of said working members toward the other to compress the pulp between them, means for imparting a translatory gyratory motion to said upper working member about an axis extending in the direction of compression to roll nodules of pulp traversing on the working surfaces from the place of entry of the pulp onto the lower working member to a discharge zone around the periphery of the lower working member, a rotary turntable surrounding the lower working member to receive the discharged pulp, means for rotating the turntable, a hopper, means for sweeping pulp off the turntable into the hopper, and a conduit for conducting liquid, which is expressed from the pulp through the drainage plate, into the hopper to wash the processed pulp out of the hopper.

6. In a machine for processing papermaking pulp, a perforated drainage plate, an inlet disposed centrally of said drainage plate through which an aqueous slurry of pulp may be delivered to said drainage plate, a lower working member having a working surface surrounding said drainage plate, an upper working member having a working surface overlying the lower working member and having opposed relation thereto, both said working members having their opposed working surfaces roughened to provide traction for nodules of pulp without obstructing rolling traverse of the nodules on said opposed faces, sweep means for moving thickened pulp

from said drainage plate onto the working surface of the lower working member, means for pressing one of said working members toward the other to compress the pulp between them, means for imparting a translatory gyratory motion to said upper working member about an axis extending in the direction of compression to roll nodules of pulp traversing on the working surfaces from the place of entry of the pulp onto the lower working surface to a discharge zone around the periphery of the lower working member, a rotary turntable surrounding the lower working member to receive the discharged pulp, means for rotating the turntable, a hopper, means for sweeping pulp off the turntable into the hopper, and a conduit for conducting liquid, which is expressed from the pulp through the drainage plate, into the hopper to wash the processed pulp out of the hopper, and a valve for controlling the flow of liquid out of the conduit into the hopper, said valve being adjustable to control by back-pressure the movement of pulp through the machine.

7. In a machine for processing papermaking pulp, a pair of opposed working members arranged to form therebetween a working space, both said working members having tiny, spaced protuberances on their opposed faces which project into said working space less than half the depth of said working space so as to provide traction for nodules of the pulp without obstructing rolling traverse of the nodules on the working members, means for pressing said members toward one another to compress pulp between their opposed faces, means for imparting a translatory, gyratory motion to one of said working members about an axis extending in the direction of compression, the working face of said one working member having a central portion internally dished away from the opposed working face of the other working member, the opposed area of the other working member being inclined to said internally dished portion at an angle no greater than the angle between said internally dished portion and a plane perpendicular to said axis, and an inlet disposed centrally of one working member for delivering pulp between the opposed faces of said working members, the protuberances on the dished portion of the gyratory working member and on the opposed portion of the other working member being inclined away from said inlet to direct the pulp from said inlet toward a discharge zone around the periphery of said other working member.

8. In a machine for processing papermaking pulp, a perforated drainage plate, an inlet disposed centrally of said drainage plate through which an aqueous slurry of pulp may be delivered onto said drainage plate, a lower working member having a working surface surrounding said drainage plate, an upper working member having a working surface overlying the working surface of the lower working member and arranged in opposed relation thereto, a sweep arm rotatable about an axis coaxial with said inlet for sweeping thickening stock up off said drainage plate and moving it onto the working surface of the lower working member, a plurality of nozzles disposed around said drainage plate for injecting steam into thickened pulp delivered onto the working surface of the lower working member, means for pressing one of said working members toward the other to compress pulp between their working surfaces, and means for

13

imparting a translatory gyratory movement to the upper working member about an axis extending in the direction of compression to roll pulp on and over the working members.

9. In a machine for processing papermaking pulp, a perforated drainage plate, an inlet disposed centrally of said drainage plate through which an aqueous slurry of pulp may be delivered onto said drainage plate, a plurality of straps secured obliquely on said drainage plate 10 with their leading edges tangent to a circle concentric with said inlet, a lower working member surrounding said drainage plate, a sweep arm rotatable about an axis coaxial with said inlet for sweeping thickening pulp up off said drainage 15 plate and moving it onto the lower working member, said sweep arm being spirally curved about said axis in the opposite direction to the direction of inclination about said axis of said straps, an upper working member overlying the lower 20 working member and disposed in opposed relation to both the sweep arm and the lower working member and cooperating with both, means for pressing the upper working member toward the lower working member and the sweep arm to 25

14

compress pulp between them, and means for imparting a translatory, gyratory motion to the upper working member about an axis extending in the direction of compression.
